UNITED STATES PATENT OFFICE

165,832

ELECTRIC FAN

Burton Franklin, Toledo, Ohio, assignor, by
mesne assignments, to Tropic-Aire, Inc., Chi-
cago, Ill., a corporation

Application July 25, 1950, Serial No. 11,398

Term of patent 14 years

(Cl. D26—7)

To all whom it may concern:

Be it known that I, Burton Franklin, a citizen of the United States, residing at Toledo, State of Ohio, have invented a new, original, and ornamental Design for an Electric Fan, of which the following is a specification, reference being had to the accompanying drawing, forming a part hereof.

Fig. 1 is a front perspective view of a casing for an electric fan, showing my new design.

Fig. 2 is a rear perspective view thereof.

Fig. 3 is a perspective of the electric fan shown in Fig. 1 but with the removably mounted base in position as a top deflector and with the casing axis vertical rather than inclined as in Fig. 1.

The dominant features of my design reside in that portion shown in full lines on the drawing.

I claim:

The ornamental design for an electric fan, as shown and described.

BURTON FRANKLIN.
